UNITED STATES PATENT OFFICE.

THOMAS E. COLLINS, OF CHICAGO, ILLINOIS.

FIRE-DOOR.

1,237,300.

Specification of Letters Patent. Patented Aug. 21, 1917.

Application filed November 26, 1915. Serial No. 63,435.

To all whom it may concern:

Be it known that I, THOMAS E. COLLINS, a citizen of the United States, residing at Chicago, in the county of Cook and State 5 of Illinois, have invented a certain new and useful Improvement in Fire-Doors, of which the following is a full, clear, concise, and exact description, reference being had to the accompanying drawings, forming a part of 10 this specification.

My invention relates to fire doors and more particularly to spring means for starting the rolling shutters of fire doors and the like.

15 I have found that in attempting to balance the rolling shutters by means of coiled springs held within the drums of the shutters it is not practically possible to completely balance the tension of the spring and the pull of the shutter at all times, although it is possible to counterbalance the curtain over most of the range of its movement. However, I find that for the top quarter of 20 the distance that the shutter moves the springs will be stronger than the shutter and this tendency is most markedly exhibited when the shutter is completely rolled up. I have also found that during the last quarter of its movement the tension of the 25 spring again tends to become greater.

That is to say, the shutter is heavy at the central part of its movement, and light at both top and bottom parts.

Due to these characteristics of a rolling 35 shutter which is spring balanced, the prior art has generally found it necessary to employ some means to start the shutter from its position of rest, as the tension of the counterbalancing spring is stronger than the 40 pull of the shutter in this position, and it is necessary to start the curtain down after which it continues to close completely. One of the devices to which I might call attention is the structure shown and described in 45 the copending application of Barry & Collins, Serial No. 841,241, filed May 27th 1914, in which a weighted bar is dropped upon the end of the curtain in order to start the same.

50 No particular difficulty is experienced after the curtain is once started but due to the preponderance of spring tension over the weight of the shutter, when the shutter is rolled up, I have found it advisable to 55 employ some means acting through only a

short distance, tending to aid the curtain to start from its position of rest.

In other devices, of the prior art, the curtain is held up by spring tension or by weights and automatically released from 60 the spring or weight by a fusible link or the like. I have found that these devices are such as are not reliable and often fail to operate due to the tendency to rust fast or due to the stiffness they possess after 65 remaining quiet for a length of time. This stiffness or rusting prevents starting of the shutter and consequent failure of operation.

In the accompanying drawings which 70 form a part of the present specification, I have illustrated a manner in which my invention may be practised.

Figure 1 is a fragmentary front elevation showing the top sill of a door-frame, having the spring drum and guideways of a 75 rolling shutter applied thereto, and provided with the spring starting means, which I shall describe later.

Fig. 2 is a cross-sectional view of a door-frame and spring balanced shutter and the 80 automatically releasable means for releasing the shutter;

Fig. 3 illustrates an automatic spring shutter of the type disclosed in the application of Barry & Collins, as above mentioned, 85 showing also the manner of applying the spring starting means;

Fig. 4 is a shutter of the type shown in Fig. 2, employing a different automatic releasing means;

Fig. 5 is an end view with a part broken away showing a different manner of mounting the springs;

Fig. 6 is a fragmentary perspective view of a different type of spring, as applied to 95 the shutter; and

Fig. 7 is a front elevation of the door shown in Fig. 5.

The flexible shutter 1 is composed of a number of metallic strips or laths hinged together and wound upon a central drum 2. This drum is mounted in suitable brackets 3, 4, which are secured to the wall of the building immediately above the top of the door opening and preferably secured to the 100 upper door sill 5.

The curtain 1 has at its end a flange or channel 6, which is shown in dotted lines in Fig. 1, this channel being arranged to project into the frame of the door and to en- 110

gage the lintel 5 or a suitable stationary part when the curtain 1 is completely rolled up. A coöperating angle-bar 7 is secured opposite the channel 6 and provides suitable attaching means for handles or the like. The bars 6 and 7 may be cut away or have projecting parts lying within the groove 8, formed between the flanges 9 and 10 of suitable angle-bars that form guides or ways 11 and 12 on each side of the door opening. A starting spring, preferably composed of two curved leaves, 14 and 15, is secured to the sill 5 in such position as to be engaged by the flange or channel 6 when the curtain is rolled up. The ends of the spring leaves 14 and 15 are slotted and are secured together by suitable bolts or rivets 16. This particular form of spring is advantageous in this connection in that it may be pressed quite flat without injury to the leaves thereof. It is further to be noted that the resistance of the spring increases greatly as the same is flattened out. This is of particular advantage as it is required that the spring give a very marked downward push when the curtain is completely rolled up but that its action diminish quite rapidly after the curtain is started.

The curtain, shown in Figs. 1 and 2, is not completely counterbalanced by the spring drum 2, in fact, it is sufficiently unbalanced that the curtain 1 will close of its own weight when the drum 2 is released, provided that it be given a start downward.

The end of the drum 2 is provided with a ratchet wheel 17 which is engaged by a stationary pawl 18 pivoted at 19. The forward end of the pawl 18 extends out over a rod 20 which is pivoted at its lower end to the end of the lever 21. The lever 21 is provided at its outer end with a weight 22 and is pivoted at 23 so that when the weight is released, it will drop down and thrust the rod 20 upward, disengaging the pawl 18 from the ratchet 17. The weight 22 is normally held upward by a wire 23, which is secured to a bracket 24, this wire or cable 23 having a fusible link 25 therein, which link is adapted to be destroyed by a dangerous temperature. The inner end of the lever 18 is provided with a cable or wire 26 for releasing the pawl 18 by hand when it is desired to close the shutter manually. Regardless of the manner of release, that is, whether it is manual or automatic, the elliptical spring 13 gives the end of the curtain a downward thrust sufficient to start the same, and thus allow it to close of its own weight. The starting spring may be employed to advantage in the type of door shown in Fig. 3 so that the starting weight may be reduced in size. In this type of door, the drum 2 is geared to a centrifugal governor 27 so that the door will not close too rapidly and so that no damage will be

done when the door strikes the bottom of the door-frame. This type of door is designed to close with maximum speed, but the starting of the door is slow due to the fact that the spring must be strong enough to hold the shutter counterbalance during most of the distance of drop. The door is started by means of the bar 28 being dropped into the channel 6 automatically when a given temperature is exceeded.

The bar 28 is suspended from a shaft 29 which is automatically releasable by a fusible link or the like. Due to the fact that the shutter 1 is held up by the tension of the spring drum with considerable force, the starting of the shutter is slow. When, however, the spring 13 is interposed between the ends of the curtain and the sill 5, starting is accelerated to such a degree that the weight of the bar 28 may be reduced and the consequent inconvenience of a heavy bar may be avoided.

In Fig. 4, I have illustrated the manner in which the spring 13 may be completely inclosed between the channel 6 and a bar of angle iron 30 which is secured to the bottom of the top door sill 5. The releasing means employed in this form of a device consists of a lever 31 pivoted at 32 and provided at its inner end with a starting or releasing weight 33 and a pawl or finger 34 which engages the teeth of the ratchet wheel 17. The end 35 of the pawl 34 is made of a brass pin so that there will be no danger of the parts rusting together. The outer end of the lever 31 is counter-balanced by a weight 36 which is suspended from the end of the arm by wire 37, or the like, having a fusible link 38. It can be seen that as soon as the fusible link 38 is destroyed, the counterbalancing weight 36 is disconnected from the end of the lever 31 and the releasing weight 33 withdraws the pawl 34 from the ratchet 17 and the curtain is then started downward by the thrust of the spring 13. The curtain, after it is started, continues its downward movement due to the fact that the weight of the curtain overbalances the tension of the spring drum.

In Fig. 5 I have shown a different manner of mounting the spring 13. In this case the spring is secured to the flange 7 on the end of the curtain 1 and when the curtain is up, the spring is compressed between the flange of the bar 7 and a bar 40 which is mounted on the ways 11, 12. It is to be understood that a plurality of springs 13 may be employed and that these springs may be helical springs, coil springs or any suitable type of spring to suit the condition to be met.

While I have shown my invention and described the same in connection with the details of particular constructions, it is to be understood that I do not intend to limit my

invention to only the forms shown, nor to the particular dimensions and proportions illustrated, but intend that all such variations and modifications as will suggest themselves to one skilled in the art be considered as coming within the spirit and scope of my invention.

What I claim is:

- 5 1. In combination, a rolling shutter, a spring drum for said shutter, said shutter having a flange at the end thereof, a spring on said flange, a stationary abutment adjacent the top of the door, said spring being compressed between said abutment and the flange on the end of the shutter, when the shutter is rolled up.
- 10 2. In combination, a rolling shutter, a spring drum for said shutter, the spring tension of said drum exceeding the weight of the shutter when the same is rolled up; said
- 15
- 20

shutter having a flange on the end thereof, a spring for starting said shutter, a stationary abutment at the top of the door opening, said spring being compressed between said abutment, and the flange when 25 the shutter is rolled up and automatic means for releasing said shutter to allow said spring to operate.

3. In combination, a rolling shutter, a stationary abutment near the top of said 30 door opening, a spring drum for said shutter, said shutter having a flange at the end thereof and a spring secured to said flange and engaging said abutment when said shutter is rolled up, said spring comprising a 35 curved leaf.

In witness whereof, I hereunto subscribe my name this 22nd day of Nov. A. D. 1915.

THOMAS E. COLLINS.
